(57) **CLAIM**

The ornamental design for a protective jacket, as shown and described.

DESCRIPTION

FIG. 1 is a perspective view of a protective jacket in accordance with an embodiment of the present invention;

FIG. 2 is a front view of the protective jacket of FIG. 1;

FIG. 3 is a rear view of the protective jacket of FIG. 1;

FIG. 4 is a left side view of the protective jacket of FIG. 1;

FIG. 5 is a right side view of the protective jacket of FIG. 1;

FIG. 6 is a top view of the protective jacket of FIG. 1; and,

FIG. 7 is a bottom view of the protective jacket of FIG. 1.

The broken line showing on the protective jacket is included for the purpose of illustrating portions of the article that forms no part of the claimed design.

1 Claim, 7 Drawing Sheets
